(57) **CLAIM**

The ornamental design for a handrail rosette, as shown and described.

DESCRIPTION

FIG. 1 is a left-side, top perspective view of a handrail rosette.

FIG. 2 is a right-side, bottom perspective view thereof.

FIG. 3 is a front bottom view thereof.

FIG. 4 is a rear view thereof.

FIG. 5 is a left-side view thereof.

FIG. 6 is a right-side view thereof.

FIG. 7 is a top view thereof; and,

FIG. 8 is a bottom view thereof.

The broken lines shown FIGS. 1-8 illustrate portions of the handrail rosette that form no part of the claimed design. The additional broken lines that illustrate the diagonal shape on the front of the handrail rosette illustrate environment and form no part of the claimed design.
